UNITED STATES PATENT OFFICE

99,817

DESIGN FOR A STOKER HOUSING

John E. Martin, La Grange, Ill., assignor to Link-Belt Company, Chicago, Ill., a corporation of Illinois

Application March 12, 1936, Serial No. 61,597

Term of patent 7 years

To all whom it may concern:

Be it known that I, John E. Martin, a citizen of the United States, residing at La Grange, in the county of Du Page, and State of Illinois, have invented a new, original, and ornamental Design for a Stoker Housing, of which the following is a specification, reference being had to the accompanying drawing, forming part thereof.

The figure is a perspective view of a stoker housing showing my new design. The reverse side of the housing is like the side shown.

I claim:

The ornamental design for a stoker housing, substantially as shown and described.

JOHN E. MARTIN.
